UNITED STATES PATENT OFFICE.

CHARLES LEA, OF BOSTON, MASSACHUSETTS, ASSIGNOR TO SHAWMUT ENGINEERING COMPANY, OF BOSTON, MASSACHUSETTS, A CORPORATION OF MASSACHUSETTS.

SPLICING CLIP.

Application filed December 20, 1921. Serial No. 523,751.

To all whom it may concern:

Be it known that I, CHARLES LEA, a citizen of the United States, and resident of Boston, in the county of Suffolk and State 5 of Massachusetts, have invented certain new and useful Improvements in Splicing Clips, of which the following is a specification.

This invention relates to binding clips and is more especially intended for use in 10 splicing together sets of warp threads in weaving.

In practice it has been customary to tie the ends of two sets of warp threads together, but oftentimes the tying knots 15 form an obstruction which interferes with the easy passage of the threads through the eyes of the harness or other parts of the apparatus. While it has been proposed to unite the warp threads by means of binding clips instead of tying, yet in order to 20 make this method commercially feasible it is necessary to use a clip capable of rapid and economical application to the warp threads and so constructed as to present no 25 substantial obstruction to the passage of the united threads through the harness or reed and to allow clips of the same size to be used to unite a greater or less bulk of 30 warp threads with equal security.

It is a characteristic feature of the present invention that the fastening members 35 of the clip can be clinched upon the warp threads with a greater or less degree of over-lapping of their free ends without superimposing one fastening member above 40 the other, which would result in giving two thicknesses of metal outside the united threads, thus producing an objectionably 45 large obstruction at that point.

Another feature of the present construction 40 consists in the adaptability of the clip to being manufactured in continuous strips so arranged as to be rapidly and accurately 45 fed into a splicing machine constructed to sever the individual clips and clinch them around the threads to be united.

In the accompanying drawings I have 50 illustrated a preferred form embodying the principles of this invention, in which,

Figure 1 is a side elevation of a series of 55 clips formed in a continuous strip.

Figure 2 is an end elevation of such strip.

Figure 3 illustrates the method by which 60 the strip may be fed through the severing and splicing machine.

Figure 4 is a plan view showing a single clip clinched to enclose and hold two overlapping tufts of warp threads.

Figures 5, 6 and 7 show the same size 60 clips in clinched position about a progressively decreasing number of strands or threads, thereby illustrating the range of capacity of clips having this construction.

Figure 8 shows an individual clip in open 65 or unclinched position.

The individual clip itself in its preferred 70 form for use is of U-shape transversely. One of its sides is notched inwardly from 75 its edges to form a pair of tongues or prongs *a* separated by the notch, while the other side is formed into a single prong or tongue *a'* whose apex or free end lies directly opposite the space or notch between the pair of prongs *a* so that when the prongs are wrapped around or clinched upon the 80 threads *c*, *c'* to be united, the free ends of the prongs on the opposite sides can pass by or over-lap each other without being superimposed one above the other. This 85 construction results in encircling the united threads with a single thickness of metal, and as the clip imbeds itself in the relatively soft threads or strands it does not produce any obstruction or projection likely to catch against the reeds or harness through which 90 the united threads are drawn.

Furthermore, this construction results in 95 adapting clips of uniform size to be used to encircle a greater or less bulk of threads, since the considerable circumferential over-lapping of the prongs *a* in relation to the prongs *a'* allows very substantial variation 100 in the diameter or size of the eye formed by the clip when clinched. This variation in capacity is illustrated in Figures 4, 5, 6 105 and 7.

This form of clip is readily adapted to be manufactured in continuous strips, as shown 110 in Figure 1. Each side of the metallic blank or strip is provided with two series of notches, one series of notches *d* being formed to receive the opposite tongue or prong *a'*, while the other series of notches *d'*, which may be termed severing notches, serve to form a partial severance of the individual 115 clips in the strip from one another, the severing operation being made by a suitable punch in the splicing machine. It will be noticed also that the severing notches on each side are opposite each other, while the 120

prong-receiving notches are transversely off-set, the two sets of notches on each side alternating with each other. The object of this particular arrangement is to facilitate the accurate and positive feeding of the strip into the splicing machine by a feed wheel e , which, as shown in Figure 3, has four teeth, e^1 on one side of its central hub e^3 arranged in alternation circumferentially with four similar teeth e^2 on the opposite side, so that each successive tooth e^1 , e^2 of the feed wheel during its intermittent rotation will engage a severing notch in alternation on either side of the feed strip.

15. The continuous back of the strip is severable across from one severing or tooth-engaging notch to the opposite severing notch, thus forming a single or individual clip having on one side a tongue receiving recess bounded by a pair of separate prongs, and at the other side a tongue at the middle portion of the clip opposite said tongue receiving recess, and adapted to be folded or bent into said recess. In the open position before setting, the clip has no obstruction to the easy introduction of the cords or threads to be united while the setting operation brings the entire back or body portion of the clip as well as the three off-set prongs into tight engagement with the encircled threads, since by means of a simple setting die and anvil, the prongs may be forced by each other and tightly clinched around the threads so as to form a practically complete tube tightly imbedded in the body of the threads so that the presence of the clip forms no enlargement or projection beyond the surface of the united threads.

What I claim is:

40. 1. A clip strip embracing in its construction a continuous strip of sheet metal formed into an elongated U-shaped trough each side of said trough being notched or cut away to form a series of notches for engaging the teeth of a feed wheel, and having between the adjacent tooth-engaging notches alternating tongues and tongue-receiving recesses,

the tongues on one side of the strip being disposed opposite the tongue-receiving recesses on the other side, the material between 50 each tongue receiving recess and the adjacent tooth-engaging notches forming prongs off-set with relation to the aforesaid tongue, substantially as described.

2. A clip strip embracing in its construction a continuous strip of sheet metal formed into a U-shaped trough comprising a continuous back and parallel side members, each side member being notched to form tooth-engaging notches for feeding purposes between 60 which is left a projecting tongue, the material between each alternating pair of tooth-engaging notches being cut away to form tongue-receiving recesses, said tongue receiving recesses on one side being directly 65 opposite the tongues formed on the other side, substantially as described.

3. A continuous strip of material formed into a U-shaped trough and notched alternately on either side to form a series of 70 three-pronged clips integrally connected on the back of said strip and arranged so that on each side two prongs of one clip alternate with the one prong of the adjacent clip whereby the strip may be fed by a notch engaging tooth wheel and severed into individual fastening clips, substantially as described.

4. A splicing clip for uniting warp yarns comprising an elongated strip of metal bent 80 transversely at its middle portion into a U-shaped trough to form yarn-gripping members adapted to embrace opposite sides of the yarn, the yarn gripping member on one side being formed with converging side 85 edges while the other gripping member has parallel side edges and an intermediate notch adapted to receive the converging end of the other member when the clip is wrapped around the yarn, substantially as 90 described.

In witness whereof, I have subscribed the above specification:

CHARLES LEA.
